C. BUHL.
APPARATUS FOR TREATING FABRICS.
APPLICATION FILED FEB. 25, 1914.

Patented Sept. 8, 1914.

UNITED STATES PATENT OFFICE.

CAY BUHL, OF PATERSON, NEW JERSEY, ASSIGNOR OF ONE-HALF TO S. DOUGLAS
McCAUSLAND, OF PATERSON, NEW JERSEY.

APPARATUS FOR TREATING FABRICS.

1,109,819.

Specification of Letters Patent. Patented Sept. 8, 1914.

Application filed February 25, 1914. Serial No. 820,907.

To all whom it may concern:

Be it known that I, CAY BUHL, a subject of the King of Denmark, residing at Paterson, in the county of Passaic and State of New Jersey, have invented certain new and useful Improvements in Apparatus for Treating Fabrics, of which the following is a specification.

This invention relates to apparatus for treating fabrics with liquids, for instance, in such processes as dyeing, mordanting, degumming, and so forth, and it has for its object to provide an apparatus in which a fabric may be treated in a manner at once as expeditious as possible and yet calculated to produce a thorough and uniform application of the liquid to the fabric and avoid injury of any kind thereto.

To this end my invention consists in certain novel combinations of parts, substantially as hereinafter described and finally embodied in the clauses of the claim.

In the accompanying drawing, Figure 1 is a longitudinal vertical central sectional view through the improved apparatus, showing the circulating system partly in elevation; Fig. 2 is a transverse vertical sectional view, showing the superstructure in elevation; and, Fig. 3 illustrates a detail.

R is a suitable tank in which the liquid with which to treat the fabric is placed. In this tank is arranged, with its axis horizontal, a drum around which the fabric is passed and which is constructed as follows: H is a hollow cylindrical shell closed at both ends and having a hollow shaft H' whose ends project beyond the ends of the cylindrical shell to form trunnions H². The end walls H³ of said shell are extended to form flanges, as shown in Fig. 1; and extending from the one of these flanges to the other is a series of equally spaced radial walls H⁴. Extending from the one to the other of the flanges of the end walls H³ and from the one to the other of the radial walls H⁴ in each instance is a curved foraminous plate P whose longitudinal ends are bent to an acute angle inwardly, as shown in Fig. 2, and fitted into longitudinal grooves P' in the enlarged outer ends of said radial walls H⁴. Each chamber P² formed by shell H, the radial walls H⁴, the flanges of the end walls H³ and a foraminous plate P is afforded communication with the interior of the hollow shaft H' by the tubular spokes H⁵.

The trunnions H² of the aforesaid drum are journaled in stuffing boxes K set in opposite walls of the tank R.

V is a circulating system for the liquid in the tank, including a rotary pump T of any suitable type and having one end connected with one of the trunnions H² of the hollow shaft by the stuffing box U and the other end preferably divided (see Fig. 2) and connected with the bottom of the tank. The other trunnion H² of the hollow shaft has fixed thereon a gear L and a pulley N, the latter being adapted to receive a belt for rotating the pulley and hence the drum.

The fabric while being passed through the bath may have its end-portions controlled in any desired manner. I prefer, however, to employ that herein illustrated, wherein, E E' designates two pairs of brackets surmounting the sides of the tank and each pair affording upwardly convex runways as shown inclining toward the central vertical plane of the tank. On these runways, which are V-shaped in cross section, travel the rollers D, having V-shaped grooves to fit the runways as shown and supporting, revoluble therein, the trunnions C of the beams B. In bearings F are journaled the trunnions of guide beams G' against which, due to the inclination of the runways, the beams D tend to bear. The fabric A wound on either beam B extends over the adjoining beam G', thence down around the drum in the liquid, thence over the other beam G' to and around the other beam D. I find that if the liquid which is squeezed out of the fabric at the point where the receiving beam B bears on the adjoining beam G' is permitted to remain there any appreciable length of time, it is likely, especially in the treatment of certain fabrics, to discolor or otherwise undesirably mark them; to prevent such accumulation from taking place I preferably perforate the beams G', so that any liquid which would otherwise accumulate may escape through the beam; or I may employ the squeegee roller G² journaled in pivoted brackets G³ between the two beams G' so as to act on either of them, according to whether the fabric is being advanced the one way or the other through the apparatus, at a point where the expressed liquid can readily flow back into the tank. The rollers G' are provided with gears M which mesh with the gear L, it being remarked that the gears L

100

110

and M are so proportioned that the toramious surface of the shell H and the surfaces of beams G' have identical speeds.

A stationary blade O is arranged in the hollow shaft H' and held against rotation by having its extension O' secured to an arm Q fixed to a shaft S projecting from the tank. For a reason to be explained, it is desired to establish and maintain within the drum a condition of pressure which is lower than atmospheric, and in the accomplishment of this object the blade O serves to exclude the admission of air to the interior of the drum through the two spokes H' which happen to be uppermost at any time.

W is a pipe for admitting steam into the tank for the purpose of preliminarily heating the liquid therein in performing certain treatments. To preserve the liquid at the temperature at which it is initially raised by this means, without continuing the means itself in action (which might in some instances be injurious to the fabric) the pump T may be jacketed to conserve the heat.

Operation: The fabric, initially wound on, say, the right hand beam B in Fig. 1, is passed over the adjacent guide-beam G', then around the drum, then over the other guide-beam G' and attached to the other beam B. While it is being advanced in the way to be explained the pump T is kept operating, causing the liquid in the tank to circulate through the system V, the tank and the foraminous drum in the direction of the arrow in said figure. The pump serves to maintain the pressure within the drum below atmospheric, so that the full benefit of the thus comparatively considerable exterior pressure is available to force the liquid through the fabric, any possibility of the admission of atmospheric air to the interior of the drum being prevented by the employment of the blade O which acts as a valve to close the ports through the spokes H' as each two of them assume the uppermost position.

So far as I am aware, it is new in an apparatus of this character to provide in a tank or the like, a hollow foraminous means submerged in the liquid and serving to guide the fabric therethrough and means to reduce the pressure within said means below atmospheric.

It will be understood that in circulating the liquid is drawn through the fabric into the chambers P², thence through the spokes into the hollow shaft H' and thence through pump T, the system V back into the tank. The advance of the fabric through the liquid is accomplished in the present case by the rotation of the drum and, in a measure, by the rotation of the guide-beams G', said drum and guide-beams being geared together in the manner described. As the advancing of the fabric proceeds the wound mass of

fabric on the receiving beam is rotated, through the frictional engagement thereof with the adjoining guide-beam G', to wind up the fabric, while a corresponding rotation of the other wound mass of fabric, to unwind the fabric from the other beam, proceeds, the one mass increasing in diameter and the other diminishing, the inclination of the runways for the rollers D allowing the delivery beam to remain always in contact with its guide-beam G'. As the mass of fabric which is increasing in diameter of course increases in weight as the operation proceeds, such is compensated for so as to maintain the load substantially constant by forming the runways upwardly convex.

If it is desired to impart an ombre or variegated effect to the fabric the perforations in the foraminous wall of the drum may be graduated in size as shown in Fig. 3.

The drum includes a sealed space H⁶ which serves to make the drum buoyant, so that it turns with less friction in its bearings.

Having thus fully described my invention, what I claim as new and desire to secure by Letters Patent is:

1. In combination, a tank containing the liquid with which to treat the fabric, a hollow foraminous means arranged in and serving to guide the fabric through the liquid, and means to reduce the pressure within said foraminous means below atmospheric pressure.

2. In combination, a tank containing the liquid with which to treat the fabric, a hollow foraminous means arranged in and serving to guide the fabric through the liquid, and means to reduce the pressure below atmospheric at one side of the part of the fabric in contact with the first means.

3. In combination, a tank containing the liquid with which to treat the fabric, a hollow foraminous drum arranged within the liquid with its axis substantially horizontal and serving to guide the fabric through the liquid, and means to reduce the pressure within said drum below atmospheric pressure.

4. In combination, a tank containing the liquid with which to treat the fabric, a hollow foraminous drum revolvably arranged within the liquid with its axis substantially horizontal and serving to guide the fabric through the liquid, means to reduce the pressure within said drum below atmospheric pressure, and means to rotate the drum.

5. In combination, a tank containing the liquid with which to treat the fabric, a hollow drum revolvably arranged within the liquid with its axis substantially horizontal and having a foraminous cylindrical wall around and in contact with which the fabric is adapted to be extended through the liquid, means to produce a difference in pressure as

between the interior and exterior of the drum, means to rotate the drum, and means to close communication through all of the foraminous part of said wall with which 5 the fabric is not in contact.

6. In combination, a tank containing the liquid with which to treat the fabric, a hollow buoyant foraminous drum revolvably arranged within the liquid with its axis substantially horizontal and around and under 10 which the fabric is adapted to extend through the liquid, means to rotate the drum and means to produce a difference of pressure as between the interior and exterior of 15 the drum.

7. In combination, a suitable support, a rotary horizontal beam journaled therein, a horizontal fabric beam on which to wind the fabric so supported that the fabric mass 20 wound on said fabric beam is adapted to rest on the first beam, means to rotate the first beam, and guides supporting the fabric beam and having their guiding surfaces inclined toward the first beam and upwardly 25 convex.

8. In combination, with the tank and a rotary beam on which to wind the fabric after immersion in the liquid contained in

the tank, a rotary roller supporting said beam, said roller being perforated whereby 30 to allow the escape therethrough of the liquid tending to accumulate between the contiguous portions of the beam and roller.

9. In combination, a tank adapted to contain the liquid with which to treat the fabric, a hollow foraminous means arranged in and serving to guide the fabric through the liquid, a liquid conducting means connected and communicating at one end with the first 35 means and connected and communicating at 40 the other end with the tank, means to heat the liquid in the tank and a jacketed pump contained in the conducting means.

10. In combination, with a suitable support having guideways, a rotary beam having a wound fabric mass therein, rollers in which said beam is journaled arranged to roll on the guideways, a beam receiving the contact of and supporting the wound fabric mass, and means to rotate the second beam. 45 50

In testimony whereof I affix my signature in presence of two witnesses.

CAY BUHL.
